A. Y. CLARK.

RAILWAY TIE,

APPLICATION FILED JAN. 26, 1920.

1,355,891.

Patented Oct. 19, 1920.

UNITED STATES PATENT OFFICE.

ADOLPHUS Y. CLARK, OF SHORT CREEK, ARIZONA, ASSIGNOR TO SAFETY FIRST METAL TIE COMPANY, OF SALT LAKE CITY, UTAH.

RAILWAY-TIE.

1,355,891.

Specification of Letters Patent.

Patented Oct. 19, 1920.

Application filed January 26, 1920. Serial No. 354,125.

To all whom it may concern:

Be it known that I, ADOLPHUS Y. CLARK, of Short Creek, in the county of Mohave and State of Arizona, have invented certain new and useful Improvements in Railway-Ties; and I do hereby declare the following to be a full, clear, and exact description of the same, reference being had to the accompanying drawings, forming part of this specification, and to the figures and letters of reference marked thereon.

This invention relates to railway ties in which the body of the tie is made of metal and the direct supports for the rails are small cushion blocks of wood or like material, thus securing all advantages of a timber tie with the employment of a small quantity of wood. The advantages are the sound-deadening effect and elastic support of the rails; the ability to secure the rails in place with the ordinary spikes and the insulation of the rails, so as to render them capable of use in the ordinary signaling systems employing track circuits.

To this end, the invention consists in certain novel details of construction, combinations and arrangements of parts, all as will be now described, and the particular features of novelty being pointed out in the appended claims.

In the accompanying drawings:

Figure 1 is a perspective view of a tie embodying the present invention, one of the locking members being shown removed from the tie body.

Fig. 2 is a similar view of the cushion block seat or chamber, removed from the tie body.

Fig. 3 is a transverse section showing the cushion block and its chamber secured in the tie body.

Fig. 4 is a modified form of construction, one of the locking members being removed from the tie body.

Fig. 5 is a detail view of the cushion block chamber of Fig. 4.

Fig. 6 is a perspective view of another modification, one of the locking members being shown removed from the tie body.

Fig. 7 is a similar view of the cushion block chamber shown in Fig. 6.

The body of the tie is formed of sheet metal bent into substantially trough-like shape, *i. e.*, having vertical sides A and a substantially flat bottom A'. Ties of this

form possess a certain inherent resiliency which will relieve the rolling stock from vibrations incident to a rigid roadbed but to increase this effect the rails are not supported directly on the metal portions of the tie, 60 but upon cushion blocks B. To economize in the amount of metal material required in the construction of the tie, the present invention contemplates the provision of a cushion block seat or chamber C in which 65 the cushion blocks B are secured. Chambers C are secured in a trough-like body or tie in any preferred manner, the chambers in the present instance being shown as provided with a plurality of tongues c which are 70 adapted to extend through openings c' in the bottom A' of the tie and are bent back against said bottom.

The blocks are fitted in the chambers C in proper position to receive the rails and are 75 of such length as will afford sufficient strength to support the rails and retain the rail fastening means, such as ordinary spikes. These blocks are preferably formed of wood and are held down in place in the 80 tie and chamber by shoulders c² formed by slotting the sides c³ of the chambers C as at c⁴ to form tongues c⁵ which are turned down over the top of the blocks B as shown in Figs. 1 to 4. In the form shown in Figs. 6 85 and 7, the tops of the chambers are cut away to form two transverse straps c⁶, which embrace the top of the cushion blocks B. The chamber C in which the cushion blocks are seated, permits the sides A of the trough- 90 like body to be made relatively low, and by forming the cushion block retaining extensions on the chambers instead of on the sides A of the tie, the entire tie body can be formed from a comparatively narrow sheet 95 of metal, thus greatly decreasing the cost of the ties.

Longitudinal movement of the cushion blocks in the tie body is prevented by plates D fitting within the trough-like body at 100 each end of the block and interlocking with the tie. The plates may be of various forms, two of which have been illustrated. In Fig. 1 the plate has lateral extensions d which fit in slots d' in the side walls A and the lateral 105 extensions have depending portions at their outer ends which extend down on the outer side of the tie body. This form of fastening plate is made more or less resilient so that the depending portions of the lateral exten- 110

sions will firmly grip the sides of the tie body and retain the fastening plate in place without the necessity of employing other fastening means, such as nails or the like, as shown in the other figures.

In Figs. 4 and 6, the fastening plates D are provided at one end with a lateral extension d^2 which extends through an aperture d^3 in one side of the tie body and at 10 their other end with a lateral extension d^4 which is slotted as at d^5 and is adapted to be fitted into a slot d^6 in the other side of the tie body. With this construction the transverse plates are substantially locked in 15 place, it being necessary to first elevate one end of the plate and then remove it transversely through the slot d^6 in the side of the tie body to effect its total displacement. However, to prevent accidental displacement 20 of the transverse plates they may be provided with central apertures for fasteners, such as screws or nails (not shown) to retain the plates and blocks in proper relative positions. Such simple fastening members may be easily removed when the blocks 25 are to be renewed or reversed when worn on one side.

In order to permit any rain water falling in the tie body to drain off, an opening E is provided in the bottom A' of the tie body.

What I claim is:

1. A railway tie comprising a metal trough-like body, a chamber secured in said body, a cushion block seated in the chamber 35 and projecting at the top of the chamber and body to form a rail seat, tongues or extensions on the chamber adapted to be turned down over the top of the cushion block, and transverse holding plates fitting within the trough-like body at each end of 40 the block and having lateral extensions interlocking with the sides of the trough-like body to prevent relative longitudinal movement of the cushion block and body.

15 2. A railway tie comprising a metal trough-like body, said body having relatively low sides, cushion block chambers secured in said trough-like body, cushion blocks seated in said chambers and projecting 50 an appreciable distance above the sides of the trough-like body to form rail seats, tongues or extensions on the cushion block chambers adapted to embrace the top of the cushion block and transverse holding plates

fitting within the trough-like body at each 55 end of the block and having lateral extensions interlocking with the sides of the trough-like body to prevent relative longitudinal movement of the cushion blocks and body.

60 3. A railway tie comprising a metal trough-like body, one side of said body having a plurality of vertical slots therein and the other side having a corresponding number of apertures therein disposed opposite 65 said slots, cushion blocks seated in said trough-like body and projecting at the top of said body to form rail seats, means for preventing vertical displacement of said blocks, and transverse holding plates having 70 lateral extensions adapted to enter the oppositely disposed apertures and slots in the sides of the trough-like body whereby the plates will be interlocked with the sides to prevent relative longitudinal movement of 75 the block and body.

4. A railway tie comprising a metal trough-like body, one side of said body having a plurality of vertical slots therein and the other side having a corresponding number of apertures therein disposed opposite 80 said slots, cushion block chambers secured in said body, cushion blocks seated in said chambers and projecting at the top of the chambers and body to form a rail seat, 85 tongues or extensions on the cushion block chambers adapted to be turned down over the top of the blocks, and transverse holding plates having lateral extensions adapted to enter the oppositely disposed apertures 90 and slots whereby the plates will be interlocked with the sides of the tie body to prevent relative longitudinal movement of the blocks and body.

95 5. A railway tie comprising a metal trough-like body, cushion block chambers secured therein, cushion blocks seated in said chambers and projecting at the top of the chamber to form rail seats, means formed on the sides of the chamber for preventing vertical displacement of the cushion blocks, and transverse holding plates fitting within the trough-like body at each end of the blocks and having lateral extensions interlocking 100 with the side of the body to prevent relative longitudinal movement of the blocks and body.

ADOLPHUS Y. CLARK.
